UNITED STATES PATENT OFFICE.

WILLIAM A. WHITE, OF PALMETTO BLUFF, SOUTH CAROLINA.

LAMP-CHIMNEY CLEANER.

1,283,610.

Specification of Letters Patent.

Patented Nov. 5, 1918.

Application filed March 23, 1918. Serial No. 224,300.

To all whom it may concern:

Be it known that I, WILLIAM A. WHITE, a citizen of the United States, residing at Palmetto Bluff, in the county of Beaufort and State of South Carolina, have invented certain new and useful Improvements in Lamp-Chimney Cleaners, of which the following is a specification, reference being had to the accompanying drawings.

10 This invention relates to an improved lamp chimney cleaner and has for its primary object to provide a simple and efficient means whereby the interior of a lamp chimney may be quickly and thoroughly cleaned.

15 It is another and more particular object of the invention to provide a device for the above purpose having a plurality of resilient metal straps upon which the cloth, paper or other cleaning material is adapted to be engaged, and means for expanding or bowing said straps in an outward direction to engage the material with the wall of the lamp chimney as the device is revolved therein.

20 It is a further general object of my invention to provide a lamp chimney cleaner, which can be very easily and quickly arranged in operative position within the chimney or removed therefrom, the device as a whole being relatively simple in its construction, strong and durable, and capable of manufacture at relatively small cost.

25 With the above and other objects in view the invention consists in the improved combination, construction, and relative arrangement of the several parts as will be herein-after more fully described, subsequently claimed and illustrated in the accompanying drawing in which similar reference characters designate the corresponding parts throughout the several views, and wherein:

30 Figure 1 is a longitudinal section through a lamp chimney showing my improved cleaning device operatively engaged therein;

Fig. 2 is a side elevation of the device in its normal condition removed from the chimney;

35 Fig. 3 is a section taken on the line 3—3 of Fig. 2; and

Fig. 4 is a section taken on the line 4—4 of Fig. 1.

40 Referring in detail to the drawing, 5 designates a cylindrical rod, preferably though not necessarily of wood, said rod being

diametrically enlarged at one of its ends as at 6. Upon the rod 5, a second tubular rod 7 is loosely engaged for longitudinal movement, said latter rod also having an enlarged end portion 8.

9 designates a plurality of resilient or elastic metal straps which converge toward each other at one of their ends, said straps being disposed in spaced relation around the rod 7 and the enlarged end of the rod 5. The converging ends of the straps 9 are secured to the enlargement 6 of the rod 5 by means of a metal cap 10 which is engaged over said end of the rod and the terminals 70 of the straps and securely fixed to the rod by means of suitable fastening elements indicated at 11. The opposite ends of the metal straps 9 are secured upon the periphery of the enlarged end 8 of the rod 7 by 75 means of the metal band 12 extending around the end of said rod and overlying the metal straps. This band is fixed to the end of the rod by means of fastening elements 13.

80 Beyond the end 8 of the rod 7, a plate or disk 14 also preferably of wood is loosely engaged on the rod 5. An angular metal bracket member 15 is fixed to this disk, one arm of said bracket member extending in parallel relation to the rod 5 adjacent to the opening in the disk. This bracket arm is provided in one edge with a notch or recess 16. A radially projecting pin or stud 17 fixed in the rod 5 is adapted for engagement 90 in said recess for a purpose which will presently appear. This pin also prevents the disengagement of the disk 14 from the end of the rod 5.

85 In the operation of the device, assuming that the parts are in their normal positions as seen in Fig. 2, the device is inserted through the neck of the lamp chimney indicated at C until the edge of the chimney neck is engaged against the plate or disk 14. The enlarged end of the rod 5 projects 100 slightly beyond the opposite end of the chimney. It is of course understood that soaked paper, cloth strips or other material upon which a suitable cleansing agent has 105 been applied, is first wrapped around the resilient metal straps 9. The operator while holding the disk 14 with one hand, with the other hand pushes inwardly against the end of the rod 5 thereby bowing or expanding 110 the metal straps 9 outwardly and causing the paper or cloth to contact with the inner

surface of the bulged or curved portion of the chimney wall. The rod 5 is then turned in the proper direction to engage the pin or stud 17 in the notch 16 of the bracket member, whereby the rod 5 will be securely held against reverse longitudinal movement and the straps 9 maintained in their bowed or expanded condition. The disk 14 is now grasped by the operator and the device turned or revolved within the lamp chimney. In this manner, it will be apparent that all parts of the inner surface of the lamp chimney will be engaged by the cleaning material and thoroughly cleaned. In order to remove the device, it is only necessary to first turn the rod 5 in the proper direction while holding the disk 14 so as to disengage the pin 17 from the bracket number. The resilient metal straps will then return to their normal condition so that they can be withdrawn through the neck of the chimney. A dry cloth or paper is then applied upon the metal straps, and after rinsing the inner surface of the lamp chimney, the device is then engaged therein as above stated and turned to dry the surface of the chimney wall.

From the foregoing description taken in connection with the accompanying drawing, it will be seen that I have devised a very simple, serviceable and highly efficient device whereby the interior surfaces of lamp chimneys can be easily, quickly and thoroughly cleaned. The device can be readily engaged within the chimney or removed therefrom without danger of breaking or chipping the chimney. Any desired number of the resilient metal straps may be employed, and while these straps are preferably of metal, they can also be made of various other materials and may be either flat or round as desired. The several other elements

of my improved lamp chimney cleaner are also susceptible of many modifications in the form, proportion and relative arrangement thereof and I therefore reserve the privilege of resorting to all such legitimate changes as may be fairly embodied within the spirit and scope of the invention as claimed.

Having thus described my invention, what I claim is:—

1. A lamp chimney cleaner including a rod having an enlarged end portion, a tube loosely engaged upon the rod, a plurality of expansible elements fixed at one of their ends to the enlarged end of the rod and to the relatively remote end of the tube, said enlarged end of the rod limiting the expansion of said elements, and means for locking the rod and tube against return movement to their normal positions.

2. A lamp chimney cleaner including a rod having an enlarged end portion, a tube loosely engaged upon the rod, a plurality of expansible elements fixed at one of their ends to the enlarged end of the rod and to the relatively remote end of the tube, said enlarged end of the rod limiting the expansion of said elements, a disk loosely engaged upon the rod and of greater diameter than the tube, said disk affording a seat for one end of a lamp chimney, and coacting means on said disk and the rod to lock said disk and rod against movement with respect to the tube and retain said elements in expanded condition.

In testimony whereof I hereunto affix my signature in the presence of two witnesses.

WILLIAM A. WHITE.
